UNITED STATES PATENT OFFICE.

LEWIS T. CANFIELD, OF CHICAGO, ILLINOIS, ASSIGNOR TO UNION DRAFT GEAR CO., A CORPORATION OF ILLINOIS.

DRAFT-GEAR.

1,123,482.

Specification of Letters Patent.

Patented Jan. 5, 1915.

Application filed November 28, 1913. Serial No. 803,538.

To all whom it may concern:

- Be it known that I, LEWIS T. CANFIELD, a citizen of the United States, and resident of Chicago, county of Cook, and State of Illinois, have invented certain new and useful Improvements in Draft-Gear, of which the following is a specification, and which are illustrated in the accompanying drawings, forming a part thereof.
- 10 The invention relates to yokes or pockets for inclosing the shock absorbing elements for gear of a draft rigging, its object being to secure great strength coupled with simplicity of parts and ease of assembling.
- 15 The invention comprises a pocket in the form of a continuous loop and a coupler engaging stirrup passing through the forward end of the loop and having its end members provided with suitable means such as apertures and slots for receiving pins or keys for securing the stirrup to a coupler.
- 20

In the accompanying drawings, Figure 1 is a view in perspective of the pocket and stirrup; Fig. 2 is a detail vertical longitudinal section through the stirrup and forward end of the pocket; Fig. 3 is a similar view showing a modified form of construction; Fig. 4 is a sectional view on the line 4—4 of Fig. 3; and Fig. 5 is a view similar to Fig. 2, showing a further modification.

The pocket 10 is shown as oblong rectangular in form, but its shape may be varied as may be necessary to accommodate the particular construction of gear with which it is to be associated. As shown in Figs. 1 and 2, this pocket is without joint or seam, and may be made of cast or wrought metal. The stirrup 11 is made of similar metal, is 25 U-shaped in form, its base being flat and its length being substantially equal to the width of the pocket. The side members 12, 13, of the stirrup project forwardly from the pocket when the parts are assembled. They 30 are preferably tapering in form and are apertured, as shown at 14, 15, for the reception of a key which will also pass through a suitable aperture in the butt of a coupler when the latter is inserted between the stirrup sides. The sides of the stirrup may be 35 strengthened by suitable ribs, such as those

shown as extending along their margins and surrounding the apertures.

In the construction illustrated in Figs. 3 and 4, the pocket 10 will be preferably 40 made of a wrought metal strap bent to give the pocket its proper configuration, the ends of the strap meeting along the median line of the forward end of the pocket, as indicated at 16, and being provided with short 45 gibs 17, 18, which are folded inwardly. In this instance the base or cross member 19 of the stirrup is apertured, as shown at 20, to receive the gibs and thereby serve as a lock to hold the ends of the strap together and to 50 prevent the spreading of its top and bottom members. In the construction illustrated in Fig. 5, the pocket 10 is shown as made of a wrought metal strap having its ends meeting on the median line of the forward end of 55 the pocket and welded together, as represented at 21. The pocket member is adapted to receive any suitable shock-absorbing elements, whether springs or a combination of springs and friction members. The usual 60 followers will be inserted and will normally bear against the rearward end of the pocket and the other against the cross member of the stirrup. The coupler, when secured between the side members of the stirrup, will 65 bear any buffing against the forward end of the pocket and transmit buffing stresses therethrough and through the cross member of the stirrup to the forward follower. The key apertures 14, 15, may be adapted to 70 snugly receive the key or allow lateral movement therethrough as may be preferred.

I claim as my invention—

In a draft rigging, in combination, a loop 75 for inclosing a gear and being formed of a strap having its ends inturned and abutting, and provided with inturned gibs; and a U-shaped stirrup extending through the loop and having an aperture for receiving the gibs, the side members of the loop being 80 adapted to embrace and engage a coupler butt.

LEWIS T. CANFIELD.
